CLAIM

The ornamental design for a suitcase, as shown and described.

DESCRIPTION

FIG. 1 is a top, front, right side perspective view of a suitcase showing our new design;

FIG. 2 is a top, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front, right side perspective view thereof, showing the suitcase with the handle in an extended configuration;

FIG. 10 is a top, rear, left side perspective view thereof;

FIG. 11 is a top, front, right side perspective view of the suitcase, showing it in an opened configuration; and,

FIG. 12 is a top, rear, right side perspective view thereof.

The broken lines, and the lightened spaces within, shown in FIGS. 2, 4-8, and 10-12, depict portions of the suitcase that form no part of the claimed design.

1 Claim, 12 Drawing Sheets
